UNITED STATES PATENT OFFICE.

CHARLES A. DANIEL, OF PHILADELPHIA, PENNSYLVANIA.

DESIGN FOR AN AUTOMOBILE-TIRE.

44,087.

Specification for Design.

Patented May 27, 1913.

Application filed February 3, 1912. Serial No. 675,353. Term of patent 14 years.

To all whom it may concern:

Be it known that I, CHARLES A. DANIEL, a citizen of the United States, residing at No. 1421 Diamond street, Philadelphia, in the county of Philadelphia and State of Pennsylvania, have invented a certain new, original, and ornamental Design for Automobile-Tires, of which the following is a specification, reference being had to the accompanying drawing.

My design is shown in the accompanying drawings in which—

Figure I, is a plan view of the tread of

an automobile tire, showing the design as impressed upon it, while Fig. II, is a section thereof, along the line II, II, of Fig. I.

The design on the tread simulates a branching vine of which the stem occupies the central part of the perimeter.

I claim:

The ornamental design for an automobile tire as shown.

CHARLES A. DANIEL.

Witnesses:

JAMES H. BELL,
E. L. FULLERTON.
